MEANS AND METHOD OF TUBE DRAWING

Walter J. Dennis, Chicago, Ill., assignor to Vascloy-Ramet Corporation, North Chicago, Ill., a corporation of Delaware

Application January 28, 1937, Serial No. 122,854

11 Claims. (Cl. 205—7)

This invention relates generally to means and methods of tube drawing and more particularly to air cooled tube drawing mechanism.

It is conventional practice in drawing tubes to reduce the diameter thereof to move the tube between the outer peripheral surface of a mandrel and the inner annular surface of a die. When hard metals which hard metals are characterized by lower coefficients of expansion and thermal conductivity than the ferrous metals commonly used in this and similar applications, such as tungsten carbide, tantalum carbide and the like, are employed in tube drawing, considerable heat is developed and, unless this heat is properly dissipated, breakage of parts may result. In fact, one of the most serious difficulties heretofore experienced in the use of hard metal of the aforesaid type for tube drawing has been the tendency of such metal to break due to the heat developed by the frictional engagement of the tube with the hard metal. It has sometimes been the practice to mount a bushing of hard metal on a core of metal having a greater coefficient of expansion than the hard metal with the result that the heat generated by the friction of the drawing operation causes the core to expand with the resultant breaking of the bushing. This will be more readily appreciated when it is understood that the core must snugly fit the hard metal bushing in order to lend the required support for the bushing when it is subjected to great pressure during the drawing operation.

It is one of the important objects of the present invention to provide means whereby a tube may be drawn over a hard metal bushing without the inherent danger of breakage resulting from heat and to this end the invention contemplates a mandrel construction whereby heat generated by friction of the drawing operation may be rapidly dissipated.

More specifically the present invention contemplates tube drawing mechanism including a mandrel adapted to support a hard metal bushing, said mandrel being so constructed and arranged as to enable movement of air into contact with said bushing whereby to carry off excessive heat and thus maintain operating temperatures within predetermined limits.

Still more specifically the invention contemplates a mandrel which will not only snugly and securely receive and support a hard metal drawing bushing, but will enable air to be carried into direct contact with the inner periphery of the bushing in such a manner as to effectively dissipate

excessive heat from the bushing and from the vicinity thereof.

The foregoing and numerous other objects and advantages will be more apparent from the following detailed description, when considered in connection with the accompanying drawing, wherein—

Figure 1 is a central sectional view of tube drawing mechanism whereby the method of drawing contemplated by the present invention may be efficiently practiced;

Figure 2 is a transverse sectional view taken substantially along the line 2—2 of Figure 1;

Figure 3 is a fragmentary longitudinal sectional view similar to Figure 1, disclosing a modified form of mandrel; and

Figure 4 discloses still another modified mandrel construction.

Referring now to the drawing more in detail wherein like numerals have been employed to designate similar parts throughout the various figures, it will be seen that one embodiment of the present invention, whereby the improved method of tube drawing may be practiced, includes a drawing die indicated generally by the numeral 10, and this die includes a suitable hard metal drawing die proper 12 mounted within a holder 14. The die proper 12 is preferably made of hard metal, such as a hard metal alloy now obtainable on the open market, as, for example, tungsten carbide, tantalum carbide and the like. The inner diameter of the die 12 determines the external diameter of a metallic tube, such as the tube 16. The entering side of the die 12 is suitably chamfered or beveled at 18 to facilitate the drawing of the tube 16 therethrough.

Disposed in co-axial and cooperative relation with the die 12 is a die or die bushing 20 which is associated with and supported by a mandrel designated generally by the numeral 22. In Figure 1 this mandrel includes an inner core member 24 which is centrally disposed and threaded within a mandrel sleeve 26. The outer extremity of the core member 24 is provided with a head 28 designed to clampingly engage the outer end surface of the die bushing 20 when the core is tightened within the mandrel sleeve 26.

The die bushing 20 is snugly supported upon the peripheral surface of a reduced core section 30 of the core member 24. The core member 24, which is in turn rigidly supported within the sleeve 26, provides a very rigid, firm support for the die bushing in order that said bushing may withstand the severe pressure conditions developed during the drawing operation. By tighten-

ing the core member 24 within the sleeve member 26 the bushing is firmly clamped between the head 28 and a shoulder 32, as clearly shown in Figure 1.

5 The sleeve 26 is carried by a mandrel member 34, said sleeve being internally threaded to be received by a threaded reduced mandrel section 36. Particular attention is directed to the internal passages through which air may be 10 directed for the purpose of cooling the die bushing 20 during the tube drawing operation. Beginning at the left extremity of Figure 1, it will be noted that passages 38 adapted to be connected to any suitable air pressure means or pump (not 15 shown) merge with a central passage 40 in the mandrel section 36. This central passage 40 communicates with a central passage 42 provided within the core member 24, and the right extremity of this passage 42 communicates with 20 radially inclined passages 44, each of said passages 44 communicating with a companion passage 46. These passages 46 extend longitudinally and permit air to be carried into direct contact with the internal periphery of the die bushing 25 20. The left extremities of these passages 46 communicate with companion radial or discharge passages 48. A threaded plug 50 closes the outer extremities of the inclined radial passages 46 and facilitates the machining of the longitudinal 30 passage 42.

From the foregoing, it will be apparent that air which is introduced at the left end of the mandrel, passes to the right extremity thereof and then outwardly and in a reverse direction along 35 the inner periphery of the die bushing 20 and thence outwardly through the radial passages or ports 48. This expansion of air from one passage or chamber to another and the continued movement thereof is sufficient to carry away excess heat generated by the friction of the tube 40 drawing operation and positively precludes overheating of the die bushing 20. By employing the mandrel construction just described, any difference in coefficient of expansion between the core 45 member 24 and the die bushing 20 is sufficiently compensated for by the rapid dissipation of heat resulting from the translation of air to positively prevent breakage of parts.

In Figure 3 a slightly modified mandrel construction is provided and in this connection particular attention is directed to the structure of the core member indicated by the numeral 24a. This core member 24a has a central passage 42a which communicates at the right extremity with 50 inclined radial passages 44a. These radial passages 44a communicate at their outer extremities with longitudinal passages 46a which in turn communicate with companion radial ports or 55 passages 48a. The right extremity of the core member 24a is reduced and threaded to receive a clamping nut 28a which functions similarly to the head 28 of the core member 24 in tightening the die bushing 20 in place. The translation or 60 movement of air through the passages 42a, 44a, 65 46a and 48a serves to effectively carry off excess heat from the die bushing 20 generated by the friction of the tube drawing mechanism.

Figure 4 discloses still another slightly modified core construction which comprises a core member 24b having a central longitudinal passage 42b which communicates at the right extremity with inclined radial passages 44b. These radial 70 passages 44b communicate with companion longitudinal passages 46b and complementary or 75 companion radial passages 48b. A solid head

28b is adapted to clampingly secure the die bushing 20 against longitudinal displacement. The movement of air through the above mentioned passages into direct contact with the inner periphery of the die bushing 20 serves to effectively maintain the temperature of said bushing within safe limits. 5

From the foregoing description, it will be apparent that my invention contemplates improved means and methods whereby tube drawing may 10 be efficiently practiced. By causing air to be moved into direct contact with the die bushing on the mandrel during the drawing operation, temperatures are maintained within working limits and the breakage of parts heretofore experienced, because of the development of excessive temperatures, is completely obviated. 15

Obviously, the invention is not limited to the specific structural arrangement disclosed herein but is capable of other modifications and changes 20 without departing from the spirit and scope of the appended claims.

Having thus described my invention, what I claim as new and desire to secure by Letters Patent is: 25

1. In tube drawing apparatus, a mandrel structure including a non-ferrous, carbide-type hard metal annular tube drawing member, and an internal support element therefor, said parts having in association therewith passageways 30 through which air may be moved into direct contact with said drawing member, whereby to maintain said drawing member within required working temperatures during the drawing operation. 35

2. In tube drawing apparatus, a mandrel structure including a non-ferrous, carbide-type hard metal annular tube drawing member, and an internal support element therefor, said parts having in association therewith longitudinally and 40 radially disposed passageways through which cooling medium may be moved into direct contact with said drawing member and circulated externally about the same, whereby to maintain said drawing member within required working 45 temperatures during the drawing operation.

3. In tube drawing apparatus, a mandrel structure including a non-ferrous, carbide-type hard metal tube drawing member, an internal support element therefor having a chamber for 50 receiving a cooling medium in which a sufficient portion of the inner periphery of said drawing member is exposed, and an exhaust passageway communicating with said chamber and the exterior of said drawing member to circulate the 55 cooling medium externally about the tube drawing member, whereby to maintain said member within required working temperatures during the drawing operation.

4. In tube drawing apparatus, a mandrel 60 structure including a non-ferrous, carbide-type hard metal annular tube drawing member, a core member supporting said drawing member, a longitudinally extending chamber within said core member for receiving a cooling medium, a 65 plurality of longitudinally extending chambers communicating with said first chamber, a sufficient portion of the inner periphery of said tube drawing member being exposed within said last mentioned longitudinally extending chambers, and an exhaust passageway communicating with said last mentioned chambers and the exterior of said drawing member to circulate the 70 cooling medium externally about the tube drawing member and internally of the tube being 75

drawn, whereby to maintain said drawing member and the tube being drawn within required working temperatures during the drawing operation.

5. In tube drawing apparatus, a mandrel structure including a non-ferrous, carbide-type hard metal annular tube drawing member, a core member supporting said drawing member, a longitudinally extending chamber within said core for receiving a cooling medium, a plurality of longitudinal chambers positioned externally of said first chamber, a plurality of radial chambers providing communication between said longitudinal chambers, a sufficient portion of the internal periphery of said drawing member being exposed within said external longitudinal chambers, and a plurality of additional radial chambers providing communication between the external longitudinal chambers and the exterior of said core member to cause the cooling medium to circulate externally about the tube drawing member, whereby to maintain said drawing member within required working temperatures during the drawing operation when air passes through said chambers.

6. In tube drawing apparatus, a mandrel structure including a non-ferrous, carbide-type hard metal annular tube drawing member, a core member supporting said drawing member, a longitudinally extending air receiving chamber within said core member, a plurality of longitudinal chambers positioned externally of said first chamber, a plurality of radial chambers providing communication between said longitudinal chambers, and peripherally disposed discharge openings communicating with said external longitudinal chambers and with the space between the core member and the tube being drawn, a sufficient portion of the internal periphery of said drawing member being exposed within said external longitudinal chambers and a sufficient portion of the external periphery of said drawing member being exposed within the space between the core member and the tube being drawn, whereby to maintain said drawing member within required working temperatures during the drawing operation when air passes through said chambers and through the space between the core member and the tube being drawn.

50 7. In tube drawing apparatus, a mandrel structure including a non-ferrous, carbide-type hard metal annular tube drawing member, an internal support element therefor, said parts having, in association therewith passageways through which air may be moved into direct contact with said drawing member, whereby to maintain said drawing member within required working temperatures during the drawing operation, and means for clampingly engaging said annular drawing member to secure said member in position upon said internal support element.

8. The method of drawing a tube which con-

sists in longitudinally passing said tube between the outer periphery of an internally supported non-ferrous, carbide-type hard metal tube drawing member and an externally supported non-ferrous, carbide-type hard metal tube drawing member, and contemporaneously passing air longitudinally of and in direct contact with a sufficient portion of the inner periphery of the internally supported tube drawing member, whereby to maintain said internally supported drawing member within required working temperatures during the drawing operation.

9. The method of drawing a tube which consists in longitudinally passing said tube between the outer periphery of an internally supported non-ferrous, carbide-type hard metal tube drawing member and an externally supported non-ferrous, carbide-type hard metal tube drawing member, and contemporaneously passing a cooling medium longitudinally of and in direct contact with the entire length of a sufficient portion of the inner periphery of the internally supported tube drawing member and circulating said cooling medium about a sufficient portion of the external periphery of said internally supported tube drawing member, whereby to maintain said internally supported drawing member within required working temperatures during the drawing operation.

10. In tube drawing apparatus, a mandrel structure including a non-ferrous, carbide-type hard metal annular tube drawing member, a hollow core member for receiving a cooling medium, said core member having a clamping head for engaging one end of the tube drawing member, a sleeve encircling the core member for clamping the tube drawing member against the clamping head of said core member, said core member having external openings in communication with its internal opening for circulating the cooling air internally of and in direct contact with the tube drawing member, said sleeve having an exhaust opening in communication with the external opening of the core member for circulating the cooling medium externally about a portion at least of the tube drawing member.

11. In tube drawing apparatus, a mandrel structure including a non-ferrous, carbide-type hard metal annular tube drawing member, and a supporting core for said tube drawing member, said core being spaced from the tube being drawn to provide an air circulating chamber therebetween and having an internal air receiving chamber in which a sufficient portion of the inner periphery of said drawing member is exposed, passageways providing communication between the internal air receiving chamber and the space between the core and the tube being drawn whereby to maintain the tube drawing member and the tube being drawn within required working temperatures during the working operation.

WALTER J. DENNIS.
